(57) **CLAIM**

I claim the ornamental design for footwear, as shown and described.

DESCRIPTION

FIG. 1 is a perspective view of footwear, showing my new design;

FIG. 2 is a left side view thereof;

FIG. 3 is a back view thereof; and,

FIG. 4 is a perspective view thereof, shown with additional environment of use.

The dot-dot-dashed lines immediately adjacent to the shaded, claimed area illustrate boundaries of the claimed design.
